Specification for Design.

Patented July 13, 1920.

Application filed December 8, 1919. Serial No. 343,431. Term of patent 14 years.

To all whom it may concern:

Be it known that I, BRYAN D. PINKNEY, a citizen of the United States, residing at Cincinnati, in the county of Hamilton and State of Ohio, have invented a new, original, and ornamental Design for Beaters for Mixing-Machines, of which the following is a specification, reference being had to the accompanying drawing, forming part thereof.

My new, original and ornamental design for a beater for mixing machines is shown in the accompanying drawing, in which:

Figure 1 is a front elevation of a beater

for mixing machines, showing my new design;

Fig. 2 is an end elevation of the same; and,

Fig. 3 is a plan view of the same.

I claim:

The ornamental design for a beater for mixing machines, substantially as shown.

BRYAN D. PINKNEY.
